UNITED STATES PATENT OFFICE.

OSMOND A. OSMONDSON, OF SALINA, KANSAS.

COMBINATION POST-DRILL AND PORTABLE HAND-DRILL.

1,242,029.

Specification of Letters Patent.

Patented Oct. 2, 1917.

Application filed October 24, 1916. Serial No. 127,466.

To all whom it may concern:

Be it known that I, OSMOND A. OSMONDSON, a citizen of the United States, residing at Salina, in the county of Saline and State 5 of Kansas, have invented a new and useful Combination Post-Drill and Portable Hand-Drill, of which the following is a specification.

The device forming the subject matter of 10 this application is a drill actuating means, and the object of the invention is to provide a structure of this kind which, taken as an entity, is adapted to be used as a vertical, post drill, it being possible, by disassociating certain parts of the structure, to use the device as a bench drill, and by making certain other adjustments, to use the structure 15 as a hand drill.

It is within the province of the disclosure 20 to improve generally and to enhance the utility of devices of that type to which the present invention appertains.

With the above and other objects in view which will appear as the description proceeds, the invention resides in the combination 25 and arrangement of parts and in the details of construction hereinafter described and claimed, it being understood that changes in the precise embodiment of the 30 invention herein disclosed can be made within the scope of what is claimed, without departing from the spirit of the invention.

In the accompanying drawings:

35 Figure 1 shows in side elevation, a drill constructed in accordance with the present invention;

Fig. 2 is a front elevation of the drill; and

Fig. 3 is a fragmental longitudinal section 40 showing the coöperation between certain parts of the structure.

In carrying out the present invention there is provided a support 1. The support 1 is a composite structure and includes a 45 main or upper member 2 to which is applied a front strip 3 and a back strip 4. One or more securing elements 5 unite the front strip 3 and the back strip 4 with the main member 2. The front strip 3 and the back strip 4 project below the lower end of the main member 1 to define a recess 6. The back strip 4 is extended a considerable distance below the lower end of the front strip 3 and is reduced in diameter, as indicated at 50 61 to form a depending arm 7 which is re- duced in thickness to form, at the lower end of the arm, a finger 8. The support 1 includes an auxiliary or lower member 9, the upper end 10 of which is received in the recess 6 above described. Secured to the 60 rear face of the auxiliary member 9 intermediate the upper and lower ends thereof is a U-shaped clip or clamp 11. The finger 8 extends within the contour of the clip 11, and securing devices 12, which may be bolts, 65 unite the clip 11 with the auxiliary member 9.

From the foregoing it will be noted that the support 1 comprises separable parts 1 and 9. By tightening up the securing elements 5, the upper end 10 of the auxiliary member 9 may be bound in the recess 6 between the strips 3 and 4, and by tightening up the securing devices 12, the clip 11 may be bound on the finger 8. The purpose to 70 be accomplished by separating the members 1 and 9 will be manifest when the description has been further proceeded with.

A two-part arm 14 stands at right angles to the main member 2 of the support 1 and is attached thereto as shown at 15. The arm 14 is sustained by braces 16, the upper ends of which are attached as shown at 17 to the arm, the lower ends of the braces being united as indicated at 18 with the front 80 strip 3. Disposed between the constituent members of the two-part arm 14 at the outer ends thereof is a bearing 19 held in place by the securing bolt 17 and, if desired, by an additional bolt 20 passing through the 90 parts of the arm 14. Journalized in the bearing 19 is an upright shaft 21 to which is secured a fly wheel 22. Secured to the shaft 21 beneath the fly wheel 22 is a pinion 23 meshing into a gear wheel 24 carried by a 95 shaft 25 journalized in the bearing 19. As shown best in Fig. 3, the shaft 25 is equipped at its lower end with a polygonal head 26. The head 26, and corresponding parts hereinafter described, may be of any desired 100 contour but to avoid prolixity in description, it will be described as square. The square head 26 of the lower end of the shaft 25 is slidably received within a square sleeve 27 equipped adjacent its upper end with a 105 flange 28 which, coacting with the head 26, limits the downward sliding movement of the sleeve 27.

Fixed to and projecting from the auxiliary member 9 of the support 1 is a bracket 110

30, having bifurcations 31 at its outer end. Disposed below the bracket 30 and secured to the auxiliary member 9 of the support 1 is a bracket 32 which has bifurcations 33 at its outer end. The numeral 34 denotes a base bar received between the bifurcations 33 of the bracket 32, and between the bifurcations 31 of the bracket 30. The bar 34 has a rectangularly disposed upper arm 35 lying above the bracket 30. The arm 35 is secured as indicated at 36 to the base bar 34. Attached to the lower end of the base bar 34, as shown at 62 is a bearing 37. A set screw 38 is threaded into one of the bifurcations 33 of the bracket 32 and engages the base bar 34 at one side. The construction, obviously, is such that the base bar 34 and parts carried thereby are detachably supported by the brackets 30 and 32.

20 A feed screw 39 is journaled in the bearing 37 and in the arm 35 but is held against longitudinal movement therein. The feed screw 39 is manipulated by a hand wheel 40. The numeral 41 designates a work table mounted as shown at 42 to slide on the base bar 34 for adjustment. The feed screw 39 is threaded into the work table 41 and constitutes a means whereby the work table may be raised and lowered.

30 The arm 35 which is connected to the base bar 34 carries a lower bearing 43. The bearing 43 carries, as shown in Fig. 2, a laterally offset U-shaped bracket 44 to the upper end of which is connected a bearing 45 aligned vertically with the bearing 43. Disposed between the bearings 43 and 45 is a beveled pinion 46. Threaded into the bearing 43 is a sleeve 47 provided at its lower end with a hand wheel 48. A shaft 49 slides vertically in the bearing 45 and in the sleeve 47 and rotates in these elements. The shaft 49 slides longitudinally in the bevel pinion 46, but is splined thereto as shown at 50, so that when the pinion 46 is rotated, the shaft 49 will be rotated also. The lower end of the shaft 49 carries a chuck 51 adapted to receive a boring tool (not shown) whereby the work supported on the table 41 may be pierced. The chuck 51 has a shoulder 52 adapted to be engaged by the lower end of the threaded sleeve 47, so as to crowd the chuck 51 and the tool carried thereby downwardly onto the work which is supported on the table 41. The upper end of the shaft 49 is provided with a square head 53 slidably received in the square sleeve 27. It will now be obvious that the sleeve 27 constitutes a means whereby, when the shaft 25 is rotated, rotation will be imparted to the shaft 49 and to the tool in the chuck 51. The upper end of the shaft 49 carries a reduced threaded stem 54 lying within the contour of the sleeve 27. A bar 55 is secured to the arm 35 and projects downwardly therefrom, the bar 55 having an

outwardly projecting stop 56, coöperating with the hand wheel 48 of the sleeve 47, for a purpose which will be set forth herein-after.

Disposed within the contour of the bracket or yoke 44 is a beveled pinion 57 which meshes into the beveled pinion 46. The shaft 58 of the pinion 57 is journaled in the outer side of the bracket or yoke 44, and carries a threaded tip 59 of the same 75 diameter as the stem or tip 54 at the upper end of the shaft 49. A crank 60 is mounted on the tip 59 and, under the circumstance to be described hereinafter, may be mounted on the tip 54 at the upper end of the 80 shaft 49.

Let it be supposed that, as shown in Figs. 1 and 2, the structure is set up for use as a post drill. When the crank 60 is operated, rotation is imparted to the beveled 85 pinion 57, the pinion 57 driving the beveled pinion 46, and the pinion 46 rotating the drill shaft 49 (Fig. 3), because the pinion 46 is splined to the drill shaft as shown at 50. Rotation will be imparted to the square sleeve 27 by the square head 53 on the upper end of the shaft 49, and from the sleeve 27, rotation will be imparted to the shaft 25 by the square head 26 of the lower end of the shaft 25. When the shaft 25 is rotated, 95 the gear wheel 44 will drive the pinion 23, and the fly wheel 22 will be rotated, for an obvious purpose.

The threaded sleeve 47 may be fed downwardly, within the bearing 43 by rotating 100 the hand wheel 48, the lower end of the sleeve 47 coöperating with the shoulder 52 on the chuck 51 to feed the shaft 49 downwardly with respect to the work on the table 41. The shaft 49 may slide in the beveled 105 pinion 46 during this operation, since these parts are splined together as shown at 50. Further, the shaft 49 can move downwardly with respect to the sleeve 27, without breaking the operative driving connection between the parts mentioned, because the squared head 53 at the upper end of the shaft 49 is slidably received in the sleeve 27.

When the threaded sleeve 47 is moved downwardly by the hand wheel 48, the hand 115 wheel 48 ultimately engages the stop 56 on the bar 55. By this operation, the squared head 53 on the upper end of the shaft 49 is prevented from binding upon the upper end of the bearing 45. It is impossible, 120 therefore, to lock the shaft 49 against rotation, by manipulating the hand wheel 48, the consequence of such a locking being the breaking of driving or driven parts, as a skilled mechanic will understand readily. 125

Let it be supposed that it is desired to use a portion of the structure as a bench drill. Then the clip or clamp 11 is loosened, and the securing elements 5 are loosened, if necessary. The auxiliary member 9 of the 130

support 1 may then be detached from the main member 2 of the support, the squared head 53 of the shaft 49 sliding out of the sleeve 27. The auxiliary member 9 of the support may then be set up horizontally on a bench. Under the circumstances above described, the crank 60 is detached from the threaded tip 59 of the shaft 58 on the pinion 57, and is mounted on the threaded tip 54 of the shaft 49, so that the latter can be rotated from its rear end.

Let it be supposed, further, that it is desired to use the structure as a hand drill. Then, by loosening the set screw 38, the base bar 34 and parts carried thereby may be detached from the brackets 30 and 32 and from the auxiliary member 9 of the support 1.

From the foregoing it will be understood that there is disclosed in this application, a novel structure which, when completely assembled, constitutes a post drill, operating vertically, it being possible to take down the device partly and use the structure as a horizontally operating bench drill. Further, by removing the base bar 34 from the brackets 30 and 32, as hereinbefore set forth, the structure may be used as a hand drill.

For convenience in claiming the invention, the fly wheel 22, the pinion 23, the gear wheel 24 and the shaft 25 may be described briefly as an inertia driving mechanism.

Having thus described the invention, what is claimed is:—

1. In a device of the class described, a support comprising separable main and auxiliary parts; means for holding the parts of the support together detachably; an inertia drive mechanism carried by the main part of the support and including a shaft; a drill shaft mounted to rotate and to slide endwise on the auxiliary member of the support; means carried by the auxiliary member of the support for feeding the drill shaft endwise; means carried by the auxiliary member of the support for rotating the drill shaft; and a slidable connection uniting the shafts detachably for simultaneous rotation.

2. In a device of the class described, a support comprising separable main and auxiliary parts; means for holding the parts of the support together detachably; a base bar; means for holding the base bar releasably on the auxiliary part of the support; an inertia drive mechanism carried by the main part of the support and including a shaft; a drill shaft; mechanism for mounting the drill shaft to rotate and to slide endwise on the bar; bar supported means for feeding the drill shaft endwise; bar supported means for rotating the drill shaft;

and a slidable connection uniting the shafts for simultaneous rotation.

3. In a device of the class described, a support including separable main and auxiliary parts; means for releasably uniting the parts of the support; an inertia drive mechanism carried by the main part of the support and including a shaft; a drill shaft mounted to rotate and to slide endwise in the auxiliary part of the support; means mounted on the auxiliary part of the support for feeding the drill shaft endwise; a beveled pinion journaled on the auxiliary part of the support, the drill shaft being splined to the beveled pinion; a third shaft journaled in the auxiliary part of the support; a beveled pinion carried by the third shaft and meshing into the first specified beveled pinion; a sliding sleeve connecting the drive shaft and the first specified shaft for simultaneous rotation; and an operating member mounted on the third shaft, the third shaft and the sleeve received end of the drill shaft being provided with duplicate elements coacting with the operating member, whereby the operating member may be shifted to the end of the drill shaft when the sleeve is retracted and when the main and auxiliary parts of the support are disconnected.

4. In a device of the class described; a support comprising separable main and auxiliary parts; means for releasably uniting the parts of the support; an inertia drive mechanism carried by the main part of the support and including a shaft; a bearing structure constituting a portion of the auxiliary part of the support; a drill shaft mounted to rotate and to slide in the bearing structure; means carried by the auxiliary part of the support for rotating the drill shaft; a sleeve having threaded connection with the bearing structure and coacting with the drill shaft to advance the drill shaft; polygonal heads carried by the first specified shaft and by the drill shaft; a sleeve slidably coacting with the said heads to connect the drill shaft and the first specified shaft for simultaneous rotation; and a stop carried by the auxiliary part of the support and coacting with the threaded sleeve to limit the advancing movement of the sleeve and the drill shaft, thereby to prevent the head on the drill shaft from binding on the bearing structure.

In testimony that I claim the foregoing as my own, I have hereto affixed my signature in the presence of two witnesses.

OSMOND A. OSMONDSON.
